UNITED STATES PATENT OFFICE.

SOLOMON K. HINDLEY, OF WORCESTER, MASSACHUSETTS.

BOOT OR SHOE.

SPECIFICATION forming part of Letters Patent No. 268,893, dated December 12, 1882.

Application filed September 19, 1882. (No model.)

To all whom it may concern:

Be it known that I, SOLOMON K. HINDLEY, of Worcester, in the county of Worcester and State of Massachusetts, have invented a certain new and useful Improvement in Boots or Shoes, of which the following is a specification.

This invention is applicable to that class of boots or shoes known as "stitch-down" goods, in which the upper, except perhaps around the heel-seat, is turned outwardly and secured to a sole or soles by fastenings or a seam or seams outside of the upper and passing through the upper and the sole or soles; and it relates to an improved method of construction of the shank of boots or shoes, the upper of which, around the fore part, is united to one or more soles by two seams or rows of fastenings outside the body of the upper, in order to secure a strong double shank with less than the usual amount of sole and upper leather.

Heretofore in the shank in this class of work the upper has either been turned in and fastened, as in the case of pegged work, or, if the outward-turned upper has been continued to the heel-seat, where it has been fastened with but a single row of fastenings, the construction is not sufficiently strong, while if the two seams or rows of fastenings used around the fore part outside the upper are continued around the shank a wider shank than is desirable is the result.

My invention consists in fastening in the shank the outward-turned portion of the upper to the subjacent sole by a single row of stitches or fastenings outside the body of the upper and uniting the soles with a row of pegs, nails, or screws, or their equivalent, inside the line of juncture of the upper and the sole with which it is in contact.

The accompanying drawings, in which similar letters of reference indicate like parts, represent, in Figure 1, a vertical elevation of my improved shoe, with portions broken out, showing vertical sections on lines *m n* and *o p* of Fig. 2. Fig. 2 is a cross-section on line *x y*, Fig. 1. Fig. 3 is a cross-section on line *V W*, Fig. 1. Fig. 4 is a cross-section on the line *x y*, Fig. 1, showing the outside seam, *F*, carried through both soles. Fig. 5 is a view of the

bottom of the boot or shoe shown in elevation in Fig. 1, the loop of the seam *F* being concealed by a channel-flap.

In the drawings, *A* is the upper, which is turned outwardly at the line of contact with the upper sole, *B*, and is fastened thereto by a seam or row of fastenings, *F*, as is shown in Figs. 1 and 2, which seam may pass also through the bottom sole, *C*, as is shown in Fig. 4.

C is the bottom sole, applied directly beneath the sole *B*, or with filling *D* interposed.

G is a row of nails or other fastenings, passing through and uniting the soles *C* and *B*, and the filling *D*, if used.

An insole, *E*, may be used, if desired, into which the row of nails or fastenings *G* may be allowed to penetrate.

H, Fig. 3, is the outer seam, used around the fore part of the shoe outside of the seam *F*.

In constructing this shoe the upper is lasted, as usual, and is fastened around the fore part of the shoe by two or more rows of fastenings outside the body of the upper, arranged as may be desired; but only the inner row of these fastenings is carried through the shank.

The point at which the outside row or rows shall be discontinued is determined by convenience; but it will ordinarily be just behind the ball. After the bottom sole has been attached around the fore part, the filling *D*, if used, having been previously laid on, the rows of nails or fastenings *G* are inserted concentric with the outside row, *F*, but inside the line of contact of the upper with the sole and extending from just behind the ball of the shoe to the heel-seat, as shown in Fig. 5.

Channels may be cut in the bottom sole, in which the rows of fastenings *G* may be driven, so that when the flaps thereof are turned back the heads of the nails or fastenings will be concealed.

It is essential to this construction that at least two soles be used through the shank; but the soles under the fore part may be arranged, as desired, with or without a slip-sole or tap-sole.

I claim as my invention—

A stitch-down boot or shoe having the upper turned outward upon the upper sole and united

thereto around the fore part by seams or rows of fastenings outside the body of the upper, and united thereto in the shank by a single seam or row of fastenings outside the body of the upper, the upper sole and the bottom sole, in the shank, being united by a row of fastenings inside the line of contact of the upper

with the upper sole and concentric therewith, substantially as and for the purpose set forth.

SOLOMON K. HINDLEY.
